UNITED STATES PATENT OFFICE.

DANIEL SCHOENTHALER, OF AKRON, ASSIGNOR OF ONE-HALF TO HARVEY D. BLAKESLEE, OF BUFFALO, NEW YORK.

TRACE-BUCKLE.

SPECIFICATION forming part of Letters Patent No. 291,540, dated January 8, 1884.

Application filed May 18, 1883. (No model.)

To all whom it may concern:

Be it known that I, DANIEL SCHOENTHALER, of Akron, in the county of Erie and State of New York, have invented a new and useful Improvement in Trace-Buckles, of which the following is a specification.

This invention relates to an improvement in that class of trace-buckles which are composed of a buckle-frame, a tongue-bail hinged to the buckle-frame, and a bail or loop attached to the hame-tug and adapted to bear upon the pivoted tongue-frame of the buckle.

The object of my invention is to produce a buckle of this character which shall be simple in construction and capable of easy adjustment on the trace, and in which the tongue is relieved from the greater portion of the strain.

My invention consists of the improvements in the construction of the buckle which will be hereinafter fully set forth, and pointed out in the claims.

In the accompanying drawings, Figure 1 is a side elevation of my improved buckle. Fig. 2 is a longitudinal section thereof. Fig. 3 is an edge elevation of the buckle. Fig. 4 is a perspective view of the buckle.

Like letters of reference refer to like parts in the several figures.

30 A represents the hame-tug, and B the trace. C C represent the side bars of the buckle-frame; D, the front cross-bar of the buckle-frame, adapted to bear against the inner side of the trace; and E, the elevated rear cross-bar of the buckle-frame, adapted to bear against the outer side of the trace. The side bars C C may be connected by an intermediate cross-bar, d, to render the buckle-frame more rigid.

40 F represents the tongue bar or plate, arranged above the front cross-bar D of the buckle-frame, and provided with rearwardly-extending side bars f f, which are pivoted at their rear ends to lugs or ears g, formed on the side bars of the buckle-frame.

45 h is the tongue, secured to the frame on the inner side of the cross bar or plate F, and arranged to bear against the front side of

the front cross-bar D of the buckle-frame, so that this cross-bar forms a support for the 50 tongue, and relieves the tongue from backward strain, which is applied to it when the trace is taut. The cross-bar D may be provided with a curved notch or recess, i, in its front side, which forms a seat for the end of 55 the tongue.

K represents the tug-bail, which is provided with a front cross-bar k, to which the tug is attached, and side bars k', the rear ends of which are arranged between the side 60 bars f of the tongue-frame, and provided with outwardly-extending flanges or projections l, which bear upon the side bars, so that a pull on the tug will swing the tongue-plate F toward the front cross-bar D of the buckle- 65 frame and cause the trace to be clamped between the bars F and D, and the tongue to be held securely in place.

The rear ends of the side bars k' may be connected by a cross-bar, m, which bears 70 against the outer side of the trace and renders the tug-bail more rigid.

The tongue-frame F is preferably cast with a pivot, n, which engages in the openings in the ears g, and the rear ends of the cross-bars f of the tongue-frame are compressed and the pivots sprung into the ears g, whereby the tongue-frame is firmly attached to the buckle-frame.

I claim as my invention—

1. The combination, in a buckle, of a buckle-frame having a front cross-bar D and a rear cross-bar, E, a tongue-plate, F, arranged above the front cross-bar D, and having the rear ends of its side bars f, pivoted to the 85 buckle-frame, and a tug-bail having its side bars arranged between said bars of the tongue-frame, and provided with outwardly-projecting ears l, bearing upon the side bars of the tongue-frame, substantially as set forth. 90

2. The combination, in a buckle, of a buckle-frame having its front cross-bar provided with a recess or depression, a tongue-frame pivoted at its rear end to the buckle-frame, and a tongue secured to the tongue-frame and 95 arranged to bear against the front cross-bar of

the buckle-frame, in the recess thereof, substantially as set forth.

3. The combination, with a buckle-frame having a front cross-bar D, provided with a recess, i, of a tongue-frame pivoted at its rear end to the buckle-frame, and having its tongue h arranged to engage in the recess i of

the buckle-frame, and a tug-bail having ears l, which bear upon the side bars of the tongue-frame, substantially as set forth.

D. SCHOENTHALER.
